UNITED STATES PATENT OFFICE.

SWENEY MUNSON, OF FOWLER, COLORADO.

SUPERHEATER.

No. 861,137.

Specification of Letters Patent.

Patented July 23, 1907.

Application filed September 27, 1906. Serial No. 336,384.

To all whom it may concern:

Be it known that I, SWENEY MUNSON, a citizen of the United States, and a resident of Fowler, in the county of Otero and State of Colorado, have invented 5 a new and Improved Superheater, of which the following is a full, clear, and exact description.

My invention relates to superheaters designed to be used in connection with tubular locomotive boilers, and has for its object to provide a superheater having 10 an ample heating surface and adapted to permit of the passage of a large volume of steam, and to be firmly secured in the smoke box of a boiler with its center of gravity so placed as to exert the least possible strain on the boiler, and so arranged as to provide ample accom- 15 modation for the exhaust and connecting mechanism and permit free access to the ends of the boiler tubes. Such objects I accomplish by the means illustrated in the accompanying drawings, in which drawings like characters of reference indicate like parts throughout 20 the views, and in which

Figure 1 is a longitudinal section of a superheater embodying my invention, taken on the line 1—1 of Fig. 2; Fig. 2 is a vertical transverse section of the same taken on the line 2—2 of Fig. 1; Fig. 3 is a front elevation of one of the headers of the superheater; Fig. 4 is a vertical transverse section of one of the headers of the superheater, taken on the line 4—4 of Fig. 1; and Fig. 5 is a vertical longitudinal section partly broken away, of one of the sections of the superheater, taken 30 on the line 5—5 of Fig. 4.

As illustrated in the drawings, a tubular boiler 1 is provided on its forward end with a smoke box 1^a arranged in front of the boiler head 2, which is provided with tubes 3 of ordinary construction secured at their 35 ends to said head. A dry steam pipe 4 extends through the head 2 of the boiler, and is provided with a branching 4^a provided with oppositely disposed flanges 4^b, as shown in Fig. 2. The flanges 4^b of the head of the dry steam pipe are attached to corresponding flanges 5^a 40 formed on the upper ends of the rear headers 5 of the superheater. Elongated apertures 5^b extend through the rear headers, having side walls 5^d formed integral with the inner and outer walls of the rear headers. These apertures are arranged between vertical rows 45 of steam pipes 6 having a threaded engagement with the inner wall 5^a of the rear headers of the heater, as shown in Fig. 5. The steam pipes 6 are connected at their opposite ends with forward headers 7 having an inner wall 7^a to which the forward ends of the steam 50 pipes 6 are secured by means of a threaded connection, the terminals 6^a of the steam pipes being turned over against the inner wall of the forward header, as also shown in Fig. 5.

The outer wall of the forward header 7 is provided 55 with screw plugs 8 having a threaded engagement

with corresponding apertures formed in the header. These apertures so formed are arranged in line with the steam pipes of the heater so that by removing the plugs the pipes may be detached from the headers and new pipes inserted in their places. In order to dispense with the use of stay bolts between the inner and outer walls of the forward headers, parallel webs 7^b are formed on the walls of said headers so as to connect said walls together, and are provided with perforations or openings 7^c of any suitable formation, 65 which permit a free circulation of steam throughout the headers. The lower portions of the forward headers are provided with extensions or legs 9 which are mounted upon the cylinder saddle 11 and connected with cylinder supply pipes 9^b, indicated by dotted 70 lines in Fig. 1. Condensing chambers 9^a are formed in the lower portion of the extensions 9, having suitable discharge orifices and blow-off valves 10 connected therewith, and provided with discharge pipes 10^a opening into the atmosphere. The valves 10 are controlled 75 by rods 10^b which extend into the cab of the engine. The forward headers of the heaters are provided with lugs or flanges 7^d and 7^e adapted to be secured to the smoke box of the boiler. A draft plate 12 extends transversely of the lower portion of the smoke box, 80 and its rear portion is supported upon lugs 5^c formed on the lower portion of the rear headers 5, and a vertical draft plate 13 is supported at its lower end on the horizontal draft plate 12 and secured to the rear headers 5 by means of lugs 13^c. The sections of the heater 85 are spaced apart leaving a central passage-way in which is arranged the exhaust nozzle 14 and a petticoat pipe 15 which extends in line with the stack 16 and is secured to the smoke box or stack by means of hangers 15^a. By means of such central passage-way 90 and the removal of the petticoat pipe and vertical draft plate, free access may be had to the forward end of the boiler tubes so as to enable the boiler tubes to be readily cleaned or repaired.

When the device is in operation, the steam from 95 the pipe 4 enters the rear headers of the superheater and passes through the steam pipes 6 into the front headers 7, and out of said headers into the extension 9 and cylinder supply pipes 9^b. When the engine stands still for a while condensation occurs in 100 a superheater, especially if the throttle leaks at all, which is often the case, and when the engine is started the water of condensation necessarily passes through the valves, cylinders, and the exhaust nozzle, and out of the stack. This results injuriously to an engine 105 for the reason that the water in passing through the valves and cylinders washes off the oil, destroys the lubrication, and dries the walls of the cylinders, which is liable to cause the cylinders to be cut, and the packing rings of the piston to be broken. By the 110

use of the condensing chamber, however, the engineer is enabled to drain the superheater at will. When an engine is running, moreover, and the boiler primes or foams, the engineer can discharge the foam through 5 the drain pipes, thereby preventing it from going through the valves and cylinders and causing injury thereby.

Although the construction shown and described herein embodies my invention in its preferred form, 10 I do not desire to be limited to such construction as other means having similar capabilities may be used without departing from my invention. Thus the condensers may be formed independently of the headers of the superheater, and connected therewith in any 15 suitable manner, and the rear headers of the heater may if desired be made without the elongated openings 5^b. I prefer to provide the headers with such openings and webs 5^c, however, to allow a portion of the smoke, heat and cinders from the boiler tubes to 20 pass through said openings and around the rear portion of the steam pipes 6, and out through the stack, the balance of the heat going down and under the bottom of the tube headers and bottom draft plate 12, and then up between the tubes and out through the 25 stack. The webs 5^c, moreover, serve as braces to bind the inner and outer walls of the rear header together.

Having thus described my invention, what I claim as new and desire to secure by Letters Patent is:

- 30 1. A superheater comprising headers having inner and outer walls forming a steam chamber, and steam pipes connecting the inner walls of said headers, one of the headers being provided with parallel elongated apertures extending through said headers, substantially as shown and described.
- 35 2. A superheater comprising similar sections spaced apart, each having headers provided with inner and outer walls forming steam chambers, a plurality of pipes secured to the inner walls of said headers, a condensing chamber, and an exhaust valve connected with said chamber, substantially as shown and described.
- 40 3. The combination with a steam boiler provided with a smoke box, of a cylinder-saddle connected with said boiler,

and a superheater mounted upon the cylinder-saddle within said smoke box and comprising two similar sections separated from each other and provided with headers having inner and outer walls forming steam chambers, and a plurality of steam pipes connected with the inner walls of said headers and with a plurality of threaded plugs secured to the outer walls of one of the headers of each section in line with said steam pipes, substantially as shown and described. 45

4. A super-heater comprising similar sections spaced apart, adapted to be arranged on opposite sides of a petticoat pipe, each having headers provided with inner and outer end walls, and steam pipes connecting the inner walls of said headers. 50

5. A super-heater comprising similar sections spaced apart, and provided with headers having inner and outer walls, steam pipes connecting the inner walls of said headers and a vertical draft plate between said sections at the rear end thereof, substantially as shown and described. 60

6. A super-heater comprising similar sections spaced apart, having headers composed of inner and outer end walls, steam pipes connecting the inner walls of said headers, a draft plate extending vertically between said sections at the rear end thereof, and a horizontal draft plate extending under said sections at the rear end thereof, substantially as shown and described. 65

7. The combination of a smoke box, a super-heater comprising similar sections spaced from the lower portion of the smoke box, and provided with headers comprising inner and outer end walls, and steam pipes connecting the inner walls of said headers, substantially as shown and described. 70

8. The combination with a boiler, of a smoke box and a super heater comprising similar sections spaced from each other and from the lower portion of the smoke box, and provided with headers comprising inner and outer end walls, and steam pipes connecting the inner walls of said headers, substantially as shown and described. 75

9. A super-heater adapted to be arranged within a circular smoke box, and consisting of oppositely disposed similar sections, provided with headers having inner and outer walls forming a steam chamber, and steam pipes connecting the inner walls of said headers, substantially as shown and described. 80

In testimony whereof I have signed my name to this specification in the presence of two subscribing witnesses.

SWENY MUNSON.
